UNITED STATES PATENT OFFICE.

WILLIAM SEVERN, OF CHICAGO, ILLINOIS.

FLOOR-MOP.

1,173,223.

Specification of Letters Patent. Patented Feb. 29, 1916.

Application filed December 14, 1914. Serial No. 877,144.

To all whom it may concern:

Be it known that I, WILLIAM SEVERN, a citizen of the United States, residing at Chicago, in the county of Cook and State 5 of Illinois, have invented certain new and useful Improvements in Floor-Mops, of which the following is a specification.

My invention relates to improvements in mops, for oiling, polishing, dusting, or 10 cleaning floors or the like.

An important object of the invention is to provide a mop of the above mentioned character, which is practical, simple in construction, inexpensive to manufacture, and 15 is convenient in use.

20 Other objects and advantages of the invention will be apparent during the course of the following description.

In the accompanying drawings forming a part of this specification and in which like 25 numerals are employed to designate like parts throughout the same, Figure 1 is a perspective view of a mop embodying my invention, Fig. 2 is an enlarged fragmentary plan view of a portion of the twisted 30 mop head carrying frame, showing the manner in which the strands or fiber are interwoven with the wire, Fig. 3 is a central longitudinal sectional view through the pivot connection between the handle and mop 35 head carrying frame, and Fig. 4 is a transverse sectional view taken on line 4-4 of Fig. 3.

In the drawings, wherein for the purpose 40 of illustration is shown a preferred embodiment of my invention, the numeral 5 designates a preferably triangular mop head carrying frame, formed of a pair of twisted sections of wire 6 of suitable stiffness and having interwoven or twisted therewith 45 transversely arranged cords or fibers 7, as shown. The sides of the triangular mop head carrying frame converge rearwardly and are bent at their rear ends to form parallel or substantially parallel extensions 9, 50 bent preferably upwardly upon themselves

to form pivot loops or heads 10. These pivot loops or heads 10, as more clearly shown in Fig. 4, are arranged inwardly of spaced plates 11, carried by arms 12, secured to a handle socket 13. The plates 11 55 are apertured for receiving a transverse clamping pivot element or pin 14, passing through the loops 10, and having screw-threaded engagement with a clamping winged nut 15. At their upper edges, the 60 plates 11 are provided with inwardly extending flanges 16, adapted to engage with the upper portions of the loops 10 to limit the swinging movement of the socket 13 with relation to the mop head carrying 65 frame. Particular attention is called to the fact that by having the extensions 9 which engage the inner sides of the plates 11 formed of twisted strands of wire, a corrugated surface is provided which engages 70 the plates 11, whereby when the nut 15 is screwed up, the mop head carrying frame may be securely locked to the plates 11 at the desired angular position. The loops 10 are arranged side by side, in engagement 75 with each other, as shown in Fig. 4. The mop head carrying frame, being formed of twisted sections of wire, also serve to bind the fiber or strands 7 thereto, besides forming a frame of proper uniform stiffness and 80 strength throughout.

It is to be understood that the form of my invention herewith shown and described is to be taken as a preferred example of the same, and that various changes in the shape, 85 size, and arrangement of parts may be resorted to without departing from the spirit of the invention or the scope of the subjoined claim.

Having thus described the invention, I 90 claim:—

A mop of the character described, comprising a mop head carrying frame formed of longitudinally twisted sections of wire having their ends converging rearwardly 95 and bent upwardly and forwardly upon themselves providing upstanding loops, a handle socket carrying spaced apertured side plates to receive therebetween the upstanding loops and provided at their tops 100

with inwardly projecting flanges to contact with the upper ends of the upstanding loops, an adjustable clamping pivot element passing through the apertured side plates 5 and the upstanding loops, and a fibrous mop head carried by the frame.

In testimony whereof I affix my signature in presence of two witnesses.

WILLIAM SEVERNS.
